UNITED STATES PATENT OFFICE.

CHARLES P. HADLEY, OF MAYWOOD, ILLINOIS.

SHOE-POLISHING BENCH.

Application filed August 20, 1923. Serial No. 658,437.

To all whom it may concern:

Be it known that I, CHARLES P. HADLEY, a citizen of the United States, and a resident of Maywood, in the county of Cook and State of Illinois, have invented a new and Improved Shoe-Polishing Bench, of which the following is a full, clear, and exact description.

This invention relates to shoe polishing benches and has for an object to provide an improved construction which may be used as an ordinary support for a shoe during the lacing operation or may be used to support shoes during the operation of polishing thereof.

Another object of the invention is to provide a shoe polishing bench in which a removable support is provided for holding a shoe in position for easy polishing when the bench is being used as a seat by the operator.

A still further object, more specifically, is to provide a shoe polishing bench wherein a plurality of shoe supports are provided adapted to be folded to an outer position when in use and to be folded into a compartment when not in use.

In the accompanying drawing—

Figure 1 is a longitudinal vertical section 30 through a bench, disclosing an embodiment of the invention, the same being taken through Figure 2, approximately on line 1—1.

Figure 2 is a top plan view of the structure shown in Figure 1.

Figure 3 is a detail fragmentary side view showing a slightly modified form of hinge.

Referring to the accompanying drawing by numerals, 1 indicates supporting legs of any suitable kind. The legs 1 may be integral with the sides 2 and 3 if desired or independent thereof. These sides are connected together by a rear end plate 4 and by a bottom plate 5 as well as a top plate 6 extending for about half the length of the plate 5. The parts just described may be made of wood or other desired material and may be secured together in any desired manner. Co-acting with the plate 6 is a plate 7 hinged thereto by any suitable form of metal hinge or strap hinge as may be preferred. A cover of leather or other suitable material 8 is provided for the plates 6 and 7 so that a more desirable surface is presented when the bench is used as a seat.

On the plate 7 is a shoe or foot rest 9 which may be of any suitable type and which is adapted to receive a shoe when the same is to be polished while on the foot of the wearer. Where a shoe is to be polished off of the foot of the wearer, the plate 7 is folded over to the dotted position shown in Figure 1 to complete the top or seat structure of the bench whereby the operator may sit thereon in any desired manner and polish the shoe on the foot support 10. This support may be of any desired kind provided with a plate 11 having extensions 12 and 13 fitting into the clips 14 and 15 riveted or otherwise rigidly secured to the supporting bracket 16. The bracket 16 may be of any suitable shape but is preferably provided with a shoulder or section 17 whereby it may rest against the edge 18 of the shoe platform 19. This platform at its lower end is provided with a bead or flange 20 and on the inner surface is provided with a socket 21, which socket is adapted to receive the end of the bracket 16. The platform 19 is hinged to the sides 2 and 3 by suitable hinge structures 22 and 23 and is locked either in the open position shown in Figure 1 or in the dotted closed position shown in Figure 2 by a suitable locking arm 24. This arm is pivotally connected with the platform 19 and is provided with notches 25 and 26 co-acting with the pin 27 secured to the side wall 2. When the platform 19 is in the dotted position shown in Figure 2, a child or other person may place his foot on the platform and the person sitting on plate 6 may lace the shoe or otherwise operate thereon. Also a person may sit on a suitable support and place his foot on the platform 19 when in the dotted position shown in Figure 1 for lacing or for other treatment.

When the bench is not to be used in an open position as shown in Figure 1 with the foot rest exposed and ready for use, the rest 20 is removed and stored in the chamber 28 formed by the plates 4, 5 and 6, side walls 2 and 3 and associated parts. The bracket 16 is also pulled out of the socket 21 and stored in this chamber. The plate 7 is then turned over to the dotted position shown in Figure 1 whereupon the rest 9 will be automatically positioned in this chamber and finally the platform 19 is swung back to the dotted position shown in Figure 1 whereupon the chamber is entirely closed and all

of the rests and associated parts are hidden from view. Blacking, brushes and other articles may be also kept in the chamber 28.

In Figure 3, a slightly modified form of hinge is provided in which the hinge plate 29 is rigidly secured to the platform 19 by screws or other means, said plate being provided with an L-shaped slot 30 for accommodating the pivotal screw 31 which may be a wood screw or any other pivotal support. The offset part of the slot 30 acts to prevent the platform 19 from moving toward a closed position accidentally. This slot also permits the platform 19 to be properly held in a substantially vertical position when open and at the same time permits a sufficient longitudinal movement of the hinge plate 29 to allow a proper closing of the platform.

20 What I claim is:—

1. In a shoe polishing bench, a body formed with a hinged platform at one end, a shoe

rest disengageably mounted on the platform, a locking arm swingably secured to the platform, said arm being formed with a plurality of notches, and a pin carried by said body adapted to engage the respective notches for holding the platform in different positions. 25

2. In a shoe polishing bench, a body, a platform hinged to one end of the body, a socket carried by said platform, a bracket slidably fitting in said socket, said bracket having a shoulder adapted to press against the edge of said platform for supporting the 35 bracket, and means at one end of the bracket for supporting a shoe rest. 30

3. In a shoe polishing bench, a body, a bracket disengageably connected with part of the body, said bracket having a pair of 40 spaced fittings, and a shoe rest having a plate slidably fitting said fittings. 35

CHARLES P. HADLEY.
